CLAIM

The ornamental design for a camera, as shown and described.

DESCRIPTION

FIG. 1 is a front perspective view of a camera showing our new design;

FIG. 2 is a front view thereof;

FIG. 3 is a rear view thereof;

FIG. 4 is a left side elevation view thereof;

FIG. 5 is a right side elevation view thereof;

FIG. 6 is a top view thereof;

FIG. 7 is a bottom view thereof;

FIG. 8 is a rear perspective view thereof;

FIG. 9 is a front perspective view thereof, showing the display screen in a raised position; and,

FIG. 10 is a rear perspective view thereof, showing the display screen in a raised position.

The broken lines illustrating portions of the camera form no part of the claimed design.
